US00D991906S

(12) **United States Design Patent** (10) **Patent No.:** **US D991,906 S**
Cheng (45) **Date of Patent:** **** Jul. 11, 2023**

(54) **HEADPHONES**

(71) Applicant: **SHENZHEN BIGGERFIVE TECHNOLOGY CO., LIMITED**, Shenzhen (CN)

(72) Inventor: **Fangchao Cheng**, Shenzhen (CN)

(73) Assignee: **SHENZHEN BIGGERFIVE TECHNOLOGY CO., LIMITED**, Shenzhen (CN)

(**) Term: **15 Years**

(21) Appl. No.: **29/801,074**

(22) Filed: **Jul. 26, 2021**

(30) **Foreign Application Priority Data**

Jun. 25, 2021 (CN) 202130398654.5
Jul. 2, 2021 (CN) 202130417371.0

(51) **LOC (14) Cl.** **14-01**

(52) **U.S. Cl.**

USPC **D14/205**

Primary Examiner — Paula Allen Greene

CLAIM

The ornamental design for headphones, as shown and described.

DESCRIPTION

FIG. 1 is a perspective view of headphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the headphones that form no part of the claimed design.

1 Claim, 8 Drawing Sheets
